SEWING-MACHINE REPAIR VISE

Max Ingwer, New York, N. Y., assignor to Consolidated Sewing Machine & Supply Co., Inc., New York, N. Y., a corporation of New York

Application December 11, 1947, Serial No. 791,133

1 Claim. (Cl. 81—32)

1

The invention disclosed in this patent application relates to work holding devices, and special objects of the invention are to provide a practical, efficient and generally desirable form of holder for supporting a sewing machine, typewriter, electric motor or other mechanism requiring repair, in best, convenient position for working on the same.

Other objects of the invention are to provide a vise or work holding construction which will consist of but few sturdy parts adapted to be readily adjusted and secured to firmly and positively hold the article or piece of mechanism to be worked upon.

Other special objects of the invention are to provide a universal form of work holder which will be small and compact in design, to take up but small space on a bench and be out of the way when not in actual service and which with its many advantages can be inexpensively produced and assembled.

Other desirable objects attained by the invention and the novel features of construction, combinations and relations of parts involved in the invention are set forth or will appear in the course of the following specification.

The drawing accompanying and forming part of the specification illustrates a present commercial embodiment of the invention. Structure, however, may be modified and changed as regards this illustration, all within the broad scope of the invention as hereinafter defined and claimed.

Fig. 1 in the drawing is a top plan view of the work holder;

Fig. 2 is a broken part sectional side view of the same with the outline of a sewing machine held therein indicated in broken lines;

Fig. 3 is an enlarged broken sectional view taken on substantially the plane of line 3—3 of Fig. 2; and

Fig. 4 is a broken part sectional detail of a slightly modified form of construction.

The base of the holder, indicated at 5, may be of any preferred size and shape and when designed to be mounted on a bench such as shown at 6 in Fig. 2, be arranged to accommodate any required number of hold-down bolts 7.

Swiveled on the base is an upright post 8 forked at the top at 9 to accommodate the web portion 10 of a tilting head 11.

A riveted stud 12 engaged in the arms of the yoke 9 provides the pivotal support for the head and a pin 13 removably engaged in the arms of the yoke and extending through selected openings 14 in the web 10, affords means for locking and securing the head in different angular positions.

In the present illustration there are three such openings 14, enabling the head to be secured as shown in Fig. 2, in a 45° tilted position or in the horizontal or vertical positions.

2

Rectangular related flanges 15, 16, at opposite ends of the web 10, serve by engagement with opposite sides of the yoke 9 to limit the swinging movements of the head to the full vertical and horizontal positions.

The tilting head structure 11 is shown as having a cylindrical bearing 17, extending therethrough in longitudinally aligned relation over the web 10 and at a right angle to the pivotal axis 12 of the head.

Journalized in this bearing is the hub portion 18 of the inner vise jaw 19.

The outer, relatively movable vise jaw 20 is shown carried by a bolt or rod 21 sliding freely through the tubular hub portion of the inner jaw and the two jaws are confined to turn together by having overstanding, trough shaped guards or guides 22, 23, in loosely sliding relation.

The trough shaped guard 22 is shown formed as an integral outward extension of the hub portion of the inner jaw 19 and the similarly shaped but smaller guard 23 is shown formed as an inward extension of the outer jaw 20.

The jaw-carrying bolt 21 is shown as screw threaded where it extends through the hub of the inner jaw and as carrying a hand nut 24 engageable with the end of the hub 18 of the inner jaw to draw the outer jaw toward the inner jaw and secure it in holding position.

The pair of vise jaws may be secured in any angular relation to which they may be rocked by means of a clamp screw 25 screw threaded in the bearing 17 in position to engage the hub 18 of the inner jaw.

Similarly, the post 8 may be secured in the various positions to which it may be turned, by a clamp screw 26, shown in Figs. 1 and 2, turning through the socket or column portion 27 of the base into engagement with the spindle portion 28 formed at the lower end of the post.

To hold the post against accidental removal from the base, a snap ring 29 is shown in Fig. 2 engaged in a groove 30 at the lower end of the spindle in position to cooperate with a stop shoulder 31 provided at the lower end of the socket 27 for the spindle.

Similarly the hub 18 of the vise head is shown held against accidental removal from the bearing 17 of the tilting head by means of a snap ring 32 engaged in a groove 33 in the end portion of the hub where it projects from the bearing 17.

The vise jaws 19 and 20 may be shaped to fit the particular work which the vise is intended to handle.

For holding a sewing machine such as indicated at 34, Fig. 2, the inner jaw 19 may be in two parts, as shown in Fig. 1, and the outer jaw 20 in a single part, to make three point gripping engagement with the bed of the sewing machine.

On loosening the hand nut 24 the outer jaw

20 may be opened as far as desirable and during this, as well as in the subsequent movement of tightening the jaws on an inserted object, both jaws will be retained in oppositely facing relation regardless of their turning in the bearing 17 in the head. The clamp screw 25 may be either tight or loose when the object is being centered and adjusted in the vise jaws, and when tightened it will hold the jaws in any desired angular position of rotation about the axis represented by the screw bolt 21.

The tilting head may be secured in either vertical, horizontal or intermediate inclined position of the vise and it will be clear that instead of just having these three set positions, other openings 14 for the holding stud 13 may be provided in the web of the tilting head or a clamp screw may be used in place of the stud 13 to secure the tilting head in any desired angular position.

With the screw 26 released, the post 8 may be turned about its vertical axis to carry the sewing machine or other supported object into any lateral position most convenient or accessible for the repair work to be performed.

Thus it will be seen that the vise actually is capable of universal adjustment to turn the supported object over or in various different positions best suited for the work in hand.

The parts of the device are few and of sturdy construction. These are easily assembled, or disassembled, if required, and they are compactly arranged so as to take up but small space when not in use.

As Fig. 2 indicates, the head may be tilted to raise the vise into vertical position so that it will, if standing directly above the base, occupy practically no greater cross sectional dimensions than the base itself.

The spindle or pivot portion 28 of the post 8 is heavy and strong enough to carry the full load gripped in the vise and to avoid breakage in case the vise should be dropped or lowered suddenly about the horizontal pivot axis 12. For such reasons the spindle may usually be made as a separate piece, such as an accurately finished, heavy steel pin, as shown. This pin, as illustrated in Fig. 2, may be fixedly secured at 35 in a socket provided to receive it in the post 8 and turn in the socket 27 provided for it in the base or, as alternately shown in Fig. 4, the spindle or pivot stud member 36 may be fixedly secured by set screws 37 in the socket 27 in the base and be rotatably received in the socket 38 provided for it in the post. In the latter instance the clamping screw 26 is screw threaded in the socket portion of the post in position to engage that portion of the spindle on which the post is rotatably mounted.

As also shown in Fig. 4, the clamping screw 26' may enter in a grooved portion 39 of the spindle to avoid scratching, marring or indenting the cylindrical portion of the spindle on which the post rotates.

To prevent accidental separation or removal of the post from the base in the Fig. 4 construction, a set screw 40 may be provided in the socket portion of the post entering the annular groove 39 sufficiently to hold the post to the base, preferably, however, without interfering with free rotary adjustment of the post on the base.

The clamp screw 25 which secured the clamp jaws in various positions of rotary adjustment in the head, may engage in an annular groove

41 in the hub portion 18 so as to avoid marring this rotatably adjustable element. Similarly, an annular groove to accommodate the inner end of the clamp screw 26, Fig. 2, may be sunk in the cylindrical surface of the bearing spindle 28.

To avoid accidental, unintentional separation of the parts, such as might result from sudden movements of the vise when holding a heavy machine, the snap rings 29 and 32 which, in the first illustrated form of the invention, rotatably confine the post on the base and hold the hub of the clamp jaws rotatably in the head, may be of flat cross section, substantially as indicated, so that they cannot be displaced from their retaining grooves by a rolling or wedging action such as might result if they were of the usual circular cross section.

What is claimed is:

A vise head having an elongated bearing extending therethrough from one side to the opposite side, a relatively stationary jaw member at one side of said head and having a tubular hub rotatably engaged in said bearing, means for securing said hub in various positions of angular adjustment in said bearing, said relatively stationary jaw member having a jaw element disposed at one end of the elongated bearing in the vise head and at one side of the axis of said bearing, and having a guard, substantially V-shaped in cross section, provided at the opposite side of said axis and projecting away from said one side of the vise head; a bolt rod extending through said hub and slideable longitudinally therein; a companion, relatively movable jaw element on one end of said bolt rod at said one side of the axis of said bolt rod and opposed to the jaw element of the relatively stationary jaw member; said relatively movable jaw element having a guard element, substantially V-shaped in cross-section, provided on the opposite side of the axis of said bolt rod and projecting toward and in interlocking telescopic relation to the projecting guard of the relatively stationary jaw member, whereby said relatively movable jaw element will be maintained in alignment with the jaw element of the relatively stationary jaw member in the longitudinal sliding adjustment of the bolt rod; said bolt rod having a screw threaded end portion projecting from the hub at the opposite side of the vise head, and a hand nut engaged on said projecting screw threaded portion of the bolt rod and contacting an end of the hub to thereby apply thrust thereagainst for pulling the bolt rod and movable jaw element into cooperative relation with the jaw element of the relatively stationary jaw member.

MAX INGWER.
